Des. 220,794
Patented May 25, 1971

220,794

RADIO RECEIVING SET

Eligah R. Rowry, 236 2-chome, Kajino-cho,
Koganei-shi, Tokyo, Japan

Filed Nov. 13, 1969, Ser. No. 20,063

Term of patent 14 years

Int. Cl. D14—03

U.S. Cl. D56—4

F19-1

FIG-2

FIG-3

FIG-4

FIG. 1 is a perspective view of a radio receiving set embodying my new design;

FIG. 2 is a top plan view;

FIG. 3 is a front view;

FIG. 4 is a bottom plan view;

FIG. 5 is a left side view;

FIG. 6 is a right side view; and

FIG. 7 is a rear view thereof.

I claim:

The ornamental design for a radio receiving set, as shown.
